UNITED STATES PATENT OFFICE.

ROBERT A. EVANS, OF MOGOLLON, NEW MEXICO.

OIL-BURNER.

1,229,921.

Specification of Letters Patent. Patented June 12, 1917.

Application filed November 29, 1916. Serial No. 134,195.

To all whom it may concern:

Be it known that I, ROBERT A. EVANS, a citizen of the United States, residing at Mogollon, in the county of Socorro and State 5 of New Mexico, have invented certain new and useful Improvements in Oil-Burners, of which the following is a specification.

This invention relates to an improved oil burner and the principal object of the invention is to provide an oil burner so constructed that the air and the oils may be kept in the same tank, the air serving as means for feeding the oil to the mixing chamber in which it is mixed with the air 15 and the mixed air and oil then passing to the combustion chamber.

Another object of the invention is to provide an improved type of mixing chamber wherein the air and oil will be mixed thus 20 producing a combustible mixture passing through an outlet nozzle and into a combustion chamber positioned within the stove.

This invention is illustrated in the accompanying drawings, wherein:

25 Figure 1 is a view showing the structure in elevation, the combustion chamber being omitted and the pump being shown in section,

30 Fig. 2 is an enlarged view showing the mixing chamber and combustion chamber in longitudinal section, the pipe leading from the mixing chamber and nozzle communicating with the combustion chamber being shown in elevation,

35 Fig. 3 is an enlarged sectional view through the discharge nozzle,

Fig. 4 is a sectional view taken along the line 4-4 of Fig. 2, and

40 Fig. 5 is a view of the combustion chamber shown partially in side elevation and partially in longitudinal section.

The receptacle or tank 10 is provided with an inlet pipe 11 through which oil may be poured into the tank, the inlet pipe being 45 provided with a control valve 12 and a funnel 13, the funnel permitting the oil to be easily poured into the tank. An oil outlet pipe 14 leads from the bottom of the tank and is provided with a control valve 15 and 50 communicates with the head 16 of the mixing chamber 17, a control valve 18 being positioned between the valve 15 and the head 16 so that the valve 18 may be opened the proper amount and left at this point, the 55 valve 15 being opened and closed when operating the burner system.

A pump 19 is mounted upon a bracket 20 carried by the receptacle 10 and is provided with an inlet pipe 21 and an outlet pipe 22, these pipes being provided with check valves 60 23 and the pipe 22 communicating with the upper portion of the tank 10. An outlet pipe 24 leads from the top of the tank or receptacle 10 and communicates with the head 16 of the mixing chamber, the pipe being provided with the valves 25 and 26 65 which are similar to the valves 15 and 18, the valve 26 being open a certain amount so that the proportion of air and oil will be in the proper relation and the valve 25 being 70 opened and closed according to whether the device is in use or not. It will thus be seen that certain of these valves will at all times be left at a set position whereas the two remaining valves will be open or closed according to whether the machine is in operation. A gage 27 is provided so that the pressure of the air in the tank can be easily 75 ascertained. In order to actuate the pump there is provided a pitman 28 leading from the head 29 sliding in the pump cylinder and connected with the crank shaft 30 upon which there is mounted the disk 31. This disk 31 may be turned by the handle 32 or may be rotated by means of a belt leading 80 from a suitable source of power such for instance as an engine.

The mixing chamber 17 is provided with the inlet head 16 and outlet head 33, these heads being connected with the body and the 85 inlet head being provided with the air and oil inlets 34 and 35 communicating with the annular groove 36. A cylinder 37 is mounted in the body of this mixing chamber and held in place by the set screw 38 90 and is provided with grooves 39 which cross as shown in Fig. 2 and communicate at one end with the groove 36 and at the opposite end with the pocket 40 formed in the head 33. As the oil and air pass around this cylinder 37 through the cross grooves 39, the streams of oil will be broken up by the air and the mixed air and oil will pass into the chamber 40 and through the pipe 41 leading therefrom into the nozzle 42. This pipe 100 41 is provided with a control valve 43 so that the passage of the mixed air and oil can be controlled. The outlet nozzle 42 is provided with a tapered end 44 which fits into the nipple 45 leading from the head 46 105 of the combustion chamber 47 and is provided with a reduced outlet opening 48 110

through which the mixed air and oil will pass into the nipple 45 and through this nipple into the combustion chamber where it will be ignited and the flames pass out 5 through the openings 49. It should be noted that these openings 49 are formed in the upper and side portions of the combustion chamber and that therefore the flames will be well distributed thus permitting it to 10 very easily and quickly heat the stove.

When in use, the combustion chamber is placed in the fire box of the stove and the nozzle 42 is passed through the door of the stove and inserted in the nipple 45. The oil 15 is poured into the tank through the pipe 11 and the valve 12 is then closed. Valves 15 and 25 will also be closed and the pump then operated thus placing the air in the upper portion of the tank under the required amount of pressure. The valves 15 20 and 25 can now be opened and the oil and air will pass through the pipes 14 and 24 into the annular groove 36 from which they will pass through the grooves 39 into the 25 chamber 40. As previously explained, the currents of air and oil will be broken during the passage along the cylinder 37 and a good combustible mixture will enter the chamber or compartment 40 from which it 30 will pass through the pipe 41 into the nozzle 42 and out of this nozzle into the combustion chamber through the nipple 45. The proper mixture of air and oil can be obtained through opening the valves 18 and 35 26 the proper amount and, after this has once been obtained, the valves will be left at the set position and the valves 15 and 25 opened and closed when it is desired to use the device or stop the operation thereof.

40 What is claimed is:—

1. In an oil burner, a tank provided with an oil inlet, an oil outlet pipe leading from the lower portion of the tank, means for providing compressed air in the upper portion 45 of said tank, an air outlet pipe leading from the upper portion of the tank, a mixing chamber having in one end inlets for the air and oil pipes communicating with an annular groove forming a pocket, a cylinder 50 inner in the chamber provided with grooves leading from the pocket to a second pocket in the opposite end portion of the mixing chamber and intercrossing at points intermediate the length of the cylinder, and an 55 outlet pipe for the mixed air and oil leading from the second pocket.

2. In an oil burner, a source of air and oil supply, pipes leading therefrom, a mixing chamber having a hollow body, heads at

the ends of the body, the head at one end being provided with a pocket communicating with the inlets for the air and oil pipes, and the head at the opposite end of the body being provided with a pocket communicating with an outlet, and means to break the air 60 and oil into streams and lead to the pocket of the second head with the streams of air and oil intersecting.

3. In an oil burner an air and oil supply tank having oil in the lower portion 70 thereof and compressed air in the upper portion thereof, an oil outlet pipe leading from the tank, an air outlet pipe leading from the tank, a mixing chamber having a hollow body, heads at the ends of the body, 75 the head at one end being provided with an annular groove in its inner face communicating with inlets for the air and oil pipe and the head at the opposite end of the body being provided with a pocket communicating with an outlet, and means to break the air and oil into streams and lead the same to the pocket of the second head with the streams of air and oil intersecting.

4. In an oil burner, a supply tank having 80 oil in the lower portion thereof and compressed air in the upper portion thereof, an oil outlet pipe leading from the tank, an air outlet pipe leading from the tank, a mixing chamber having a housing provided at one 85 end with air and oil inlets communicating with a pocket, a cylinder within the housing provided with longitudinally extending grooves leading from the pocket and intersecting and communicating with the pocket 90 in the opposite end of the mixing chamber, and an outlet pipe leading from the second pocket of the housing.

5. An oil burner including a source of air and oil supply, pipes leading therefrom, and 100 a mixing chamber having a body, a cylinder in the body provided with mixing grooves extending longitudinally thereof in intersecting relation, a head for said body provided with air and oil inlets communicating 105 with a pocket having communication with the grooves of said cylinder, and a head for the opposite end of the body provided with a pocket to receive the mixed air and oils, the pocket of the second head communicating 110 with an outlet.

In testimony whereof I affix my signature in presence of two witnesses.
